MACHINE FOR OPERATING UPON SHEET MATERIAL

Milton H. Ballard, Beverly, Mass., assignor to
 United Shoe Machinery Corporation, Paterson,
 N. J., a corporation of New Jersey

Application December 22, 1931, Serial No. 582,570

13 Claims. (Cl. 164—23)

This invention relates to machines for operating upon sheet material and is herein illustrated as embodied in a clicking machine of the type illustrated in United States Letters Patent No. 921,503, granted May 11, 1909, upon an application filed in the name of Arthur Bates.

Machines of the type referred to commonly comprise a cutting bed, a post, and a presser arm secured to the post and movable about the axis of the post over the cutting bed, there being means for reciprocating the post to produce pressure-applying strokes of the presser arm against a die on the bed. Such machines are commonly provided with means associated with the presser arm by which an operator can move the presser arm into operative position over the heel and initiate a pressure-applying movement.

It is an object of the present invention to provide an improved clicking machine of novel construction which, without sacrificing the advantages of such machines as heretofore constructed will greatly facilitate the starting operation and will render it more uniform, thereby contributing to the efficiency of the operator.

In view of the foregoing, the clicking machine illustrated as constituting one embodiment of the invention is provided with a lever for controlling power means for causing reciprocation of a post and manually controlled means carried by a presser member or arm and movable through a predetermined distance in any of the angular positions of the presser arm to effect a movement of the lever through a constant predetermined distance. Preferably and as shown, the lever is pivotally mounted upon the frame of the machine and has a free end portion which extends into proximity to the post and which is engaged by an annular member mounted concentrically of the post and movable heightwise thereof. As shown, the manually controlled means comprises a handle pivotally mounted upon the presser arm and making connection with the annular member whereby depression of the handle will effect a movement of the annular member heightwise of the post with the result that the lever will be moved through a predetermined angle. A machine constructed as above outlined is advantageous in that operation of the starting handle in any position of the presser arm laterally of the block will result in the movement of the lever through a constant angle with the result that the starting operation is uniform. In other words, the pressure-applying operation is initiated by operation of the manually controlled means through the same predetermined distance and

with substantially the same effort regardless of where the presser arm is located. This contributes to the efficiency of the operator, in view of the fact that it relieves the operator from giving any particular consideration to the starting operation.

Other objects and features of the invention will be apparent from the following detailed specification when taken in connection with the accompanying drawings and will be pointed out in the claims.

In the drawings,

Fig. 1 represents an elevation of a portion of a clicking machine embodying the invention;

Fig. 2 is a perspective view illustrating details of the mechanism for operating the starting lever;

Fig. 3 is a plan view, partly in section, illustrating the mounting and arrangement of the starting mechanism; and

Fig. 4 is a sectional view taken along line IV—IV of Fig. 3 and illustrating details of the mounting of the starting handle.

The invention is illustrated as embodied in a machine of the type commonly known in the trade as a twin clicking machine. Since opposite ends of the machine are substantially identical, only the right-hand portion of the machine is illustrated. As shown in Fig. 1, the machine comprises a frame 10 upon which is supported a cutting bed 12 adapted to carry a cutting block 14. Positioned at one end of the frame is a post 16 to which is secured a presser arm 18, the post being mounted for rotation in the frame so that the presser arm can be moved transversely over the cutting block 14. In order to produce pressure-applying operations of the arm 18 upon the cutting bed, the post 16 is mounted for reciprocation in the frame. To this end the post is supported by a connecting rod 20 arranged to be reciprocated by an eccentric 22 upon a shaft 24, the latter being arranged to be driven by a flywheel 26 to which it can be connected at the will of the operator by suitable clutch mechanism which includes as one of its parts a clutch-control lever 28. The clutch mechanism, which is not illustrated in detail, is preferably of the one-revolution type, such as that disclosed in United States Letters Patent No. 1,011,903, granted December 19, 1911 upon an application filed in the name of Arthur Bates.

Preferably and as shown, the mechanism for initiating an operation of the presser member comprises a manually operable member or handle 30 carried by the presser arm 18 and which is

operable to actuate a lever 32 pivotally mounted upon a shaft 34 carried by the frame 10. The shaft 34 carries at its outer end a second lever 36 to which is connected a trip rod 38 which, in turn, is connected at its lower end to a lever 40 operative to elevate the clutch lever 28 to cause engagement of the fly-wheel and shaft.

The presser arm 18 comprises a main casting 42 having flanged portions 44 extending laterally therefrom to form the striking face of the presser member. Also forming part of the arm is a cap 46. The body portion 42 and the cap 46 are positioned on opposite sides of the post 16 and are clamped together on the post by a U-shaped bolt 48, the upper portion of the casting 42 being secured to the post by a U-shaped member 50. It is to be noted that the post 16 is located rearwardly of the center line of the cutting bed. This is for the purpose of providing space at the forward portion of the block for the positioning of material on the block and to prevent the obstructing of the passage of light to the block as far as is possible. In view of this, in order to provide a striking surface on the presser arm 18 which will make it possible to operate on any part of the right-hand portion of the cutting block 14, the flanges 44 are asymmetrical with respect to the body portion 42 on opposite sides thereof.

The starting handle 30 is U-shaped and has a central portion 52 extending substantially parallel to and somewhat above the forward edge of the flange 44. Extending from the portion 52 at each end thereof are two arms 54 and 56 the ends of which are pivotally mounted upon the presser arm. The arm 54 extends through an opening 58 in the presser arm 42 and is provided at its end with a bushing 60 which extends over a stud 62 positioned axially of the body portion 42 of the arm, the stud having a spherical end portion 64 which is engaged by the bushing 60. The other arm 56 has at its end an extension 66 having a countersunk bore 68 which surrounds a shaft 70 extending axially of the presser arm and mounted for rotation relatively to the arm. The shaft 70 is reduced to form a spherical portion 72 which bears against the central portion of the bore 68, there being clearance between the bore and the shaft 70 so that there can be some angular movement of the arm 56 relatively to the shaft. The arm 56 is secured to the shaft by means of a disk 74 located in a longitudinally extending slot 76 in the shaft and pivotally secured to the extension 66 by a pin 78 extending at right angles to the shaft 70. This construction provides for universal movement of the handle 30 relatively to the shaft 70 while at the same time providing a positive connection between the handle and the shaft so that the latter can be rotated by the handle. The universal mounting of the handle 30 on the stud 62 and the shaft 70 makes it possible to move the handle through a small angle while maintaining the portion 52 of the handle substantially parallel to the edge of the flange 44. An advantage of this construction is that the operator can grasp the handle close to the portion of the arm nearest to him and move the arm over the block with a minimum of effort.

In order to provide for movement of the lever 32 through the same distance regardless of the position of the presser arm, means is provided for insuring movement of the end of the lever through the same distance in each case. This means comprises a semi-annular member 80 slidably mounted upon rods 82 carried by an up-

ward extension 84 of the cap 46. The semi-annular member 80 is connected to the shaft 70 by a curved lever 86 secured to the end of the shaft 70 and making connection with the semi-annular member 80 by a link 88. Thus, upon rotation of the shaft 70 by the handle 30 the semi-annular member 80 is moved heightwise of the presser arm and post. Upon release of the handle the member is forced downwardly by a spring 90 surrounding one of the rods 82. The semi-annular member 80 is provided with a groove 92 within which is positioned a split block 94. Connection between the block and the lever 32 is made by a pin 96 carried by the lever 32 and having at its end a ball-shaped portion 98 positioned in a recess in the block 94, thus to form a universal connection. The block 94 is slidable in the groove 92 and is constantly in engagement with the groove. It is to be noted that the semi-annular member 80 is co-axial with the post and lies in a plane extending substantially at right angles to the post and to the supporting rods 82. Consequently, as the presser arm 18 is rotated about the axis of the post the block 94 remains in engagement with the member 80 without causing any change in the angular position of the lever 32 and will always be in position to rotate the lever about the shaft 34 whenever the handle 30 is depressed. Thus, the movement of the handle will result in uniform angular movement of the lever 32 irrespective of the position of the presser member laterally of the block.

As above pointed out, the lever 32 is loosely mounted upon the shaft 34. In effecting rotation of the lever 36 to operate the clutch, the shaft has fixed thereto a plate 100 loosely carrying a pin 102 which extends through a second pin 104 carried by ears 106 of the lever 32. The plate 100 is normally held against the pin 104 by a spring 108 on the pin 102. Thus, in the normal operation of the lever 32 angular movement thereof results in similar movement of the lever 36. Thus, a yielding connection is provided between the handle 30 and the trip rod 38.

In order to limit the movement of the handle 30 within the range of angular movement required to operate the clutch, the extension 66 is provided with two arms 110 and 112 extending, respectively, upon opposite sides of the shaft 70. These arms are provided with set screws 114 and 116 adapted to engage, respectively, the flange 44 and the body portion 42 of the presser arm. The set screws act as stops to limit the rotation of the shaft 70 in either direction, thus reducing the amount of lost motion of the handle during its movement to effect an operation of the clutch. Longitudinal movement of the shaft 70 is prevented by means of a set screw 118 carried by the casting 42 and extending into a recess 120 in the shaft.

The presser arm 18 is provided with a fixed handle 122 extending along the forward edge portion of the arm outwardly of and below the handle 30 to provide means for moving the arm over the block, particularly when the arm is located at the far side of the block.

The handles 30 and 122 are located adjacent to the edge portion of the presser arm and extend substantially along the entire length of the arm with the result that they are readily accessible to an operator standing in front of the machine. The handles are positioned parallel to each other and are so spaced that both handles can be grasped by the hand of the operator in moving the arm laterally of the cutting block and initia-

tion of a pressure operation can be had by a gripping action effective to rotate handle 30 about its axis. Means is provided for locking the lever 36 against movement which would initiate unauthorized operation of the machine. To this end the lever 36 is provided with a lug 124 adapted to be engaged by a set screw 126 carried by a link 128 which can be swung into or out of engaging relation by a manually operable rod 130. When the set-screw 126 engages the lug 124 depression of the starting handle 30 will result in rotation of lever 32 but since lever 36 is held against rotation the connection of the two levers will yield thereby avoiding any likelihood of breakage of parts without, however, causing an operation of the machine.

In the operation of the machine, sheet material such as leather is placed upon the cutting block 14 and a cutting die is located upon the material in position to cut a blank, at which time the presser member 18 has been moved rearwardly into position to expose the portion of the material which is to be operated upon. The operator then grasps either the handle 30 or the handle 122 or both and draws the presser member laterally over the block until it is in position above the die. The handle 30 is then depressed, which operation results in elevation of the semi-annular member 80 and angular movement of the lever 32 with the result that the clutch lever 28 is operated to cause a reciprocation of the presser member to produce a pressure-applying operation. It will be observed that the handle 30 is advantageously located along the edge of the presser member in position readily to be grasped by the operator, the operative portion of the handle being close to the edge of the presser arm throughout substantially its entire length with the result that the operator can grasp the handle at the portion thereof which is nearest to him and can depress the handle to initiate the pressure-applying operation without materially changing the position of his hand. Furthermore, since movement of the handle through a definite distance results likewise in the movement of the semi-annular member 80 through a definite distance regardless of the position of the presser member, the tripping of the clutch will be accomplished by the exertion of substantially the same force applied to the handle and acting through substantially the same distance. Consequently, the tripping of the clutch will be uniform irrespective of the location of the presser member transversely of the cutting block and will render the operation of the machine more uniform.

Having described my invention, what I claim as new and desire to secure by Letters Patent of the United States is:

60 1. A clicking machine comprising a frame, a bed, a post mounted for reciprocation relatively to the frame, a presser member carried by the post and arranged for angular movement about the axis of the post, power means for reciprocating the post to produce pressure-applying operations of the presser member upon the bed, a lever for controlling the power means, manually controlled means carried by the presser member and movable through a predetermined distance, and a connection between the manually-controlled means and the lever for effecting movement of the lever through a constant predetermined distance irrespective of the angular position of the presser member.

70 2. A clicking machine comprising a frame, a

post mounted in the frame for angular movement about its axis and for reciprocation relatively to the frame, power means for reciprocating the post, means for controlling the power means comprising a lever pivotally mounted upon the frame and having a free end which extends into proximity to the post, and means for operating the lever comprising a member having a surface adapted for continuous engagement with the lever at a point located at a constant distance from the pivotal axis of the lever.

3. A clicking machine comprising a frame, a post mounted in the frame for reciprocation relatively to the frame, power means for reciprocating the post, means for controlling the power means comprising a lever pivotally mounted upon the frame and having an end portion which extends into proximity to the post, and means for operating the lever comprising a member movable angularly about the axis of the post and adapted continuously to engage the end portion of the lever at a point located at a constant distance from the pivotal axis of the lever.

4. A clicking machine comprising a frame, a post mounted in the frame for angular movement about its axis and for reciprocation relatively to the frame, power means for reciprocating the post, means for controlling the power means comprising a lever pivotally mounted upon the frame and having an end portion which extends into proximity to the post, and means for operating the lever comprising a member carried by the post and adapted to engage the same part of said end portion of the lever in any of the various angular positions of the post.

5. A clicking machine comprising a frame, a bed, a post mounted for reciprocation relatively to the frame, a presser arm carried by the post and movable laterally over the bed, power means for reciprocating the post thereby producing pressure-applying operations of the presser arm upon the bed, means for controlling the power means comprising a lever pivotally mounted upon the frame, and means for moving the lever through a constant predetermined angle comprising a member movable with the presser arm and adapted normally throughout angular movements of the post continuously to engage the lever at a predetermined point heightwise of the post.

6. A clicking machine comprising a frame, a bed, a post mounted for reciprocation relatively to the frame, a presser arm carried by the post and arranged for angular movement about the axis of the post, power means for reciprocating the post in producing pressure-applying operations of the presser arm upon the bed, means for controlling the power means comprising a lever pivotally mounted upon the frame, means for imparting a predetermined angular movement to the lever comprising a member movable angularly about the axis of the post and positioned continuously to engage the lever at a predetermined point relatively to the pivotal axis of the lever, and manually operable means carried by the presser arm for moving the member heightwise of the post.

7. A clicking machine comprising a frame, a bed, a post mounted in the frame for angular movement about its axis and for reciprocation relatively to the frame, a presser arm secured to the post, power means for reciprocating the post in producing pressure-applying operations of the presser arm upon the bed, an annular member disposed concentrically of the post and mounted

- for movement therewith and heightwise thereof, means for initiating operation of the power means comprising a lever one end of which is adapted continuously to engage the annular member, and means for moving the annular member heightwise of the post to effect an operation of the lever.
8. A clicking machine comprising a frame, a cutting bed, a post mounted in the frame, a presser arm carried by the post, means for reciprocating the post to produce pressure operations of the arm upon the bed, a clutch member for controlling reciprocations of the post, a lever pivotally mounted upon the frame for actuating the clutch member, an annular member secured to the post and making slidable engagement with the lever, and a handle for moving the annular member in a direction to produce angular movement of the lever.
10. A clicking machine comprising a frame, a bed, a post mounted in the frame, a presser member mounted upon the post for movement laterally over the bed about the axis of the post, power means for reciprocating the presser member, a handle extending along one side of the presser member and fixedly secured thereto, and means for initiating operation of the power means comprising a movable handle carried by the presser member and extending along one side thereof in proximity to the first-mentioned handle.
15. A clicking machine comprising a frame, a bed, a post mounted in the frame, a presser member secured to the post and movable laterally over the bed, power means for reciprocating the post to produce pressure-applying operation of the presser member upon the bed, starting mechanism for the machine including a clutch, a lever pivotally mounted upon the frame and having connections with the clutch for operating the latter, an annular member embracing the post and mounted for movement heightwise thereof, said lever having a portion loosely engaging the annular member, and manually operated means for moving the annular member heightwise of the post.
20. A clicking machine comprising a frame, a work supporting bed, a post mounted in the frame, a presser member secured to the post and movable laterally over the bed, means for reciprocating the post to produce pressure-applying operation of the presser member upon the bed, starting mechanism for the machine including a clutch, a lever pivotally mounted upon the frame and having connections with the clutch for operating the latter, an annular member embracing the post and mounted for movement heightwise thereof, said lever having a portion loosely engaging the annular member, and manually operated means for moving the annular member heightwise of the post.
25. A clicking machine comprising a frame, a cutting bed, a post mounted in the frame for reciprocation relatively to the bed, a presser arm secured to the post and mounted for movement therewith transversely of the bed, a clutch member for controlling reciprocations of the post, a

bracket upon the arm, a sector mounted upon the arm for movement heightwise of the post, a member associated with the clutch member and slidably engaging the sector, and a handle on the arm for effecting movement of the sector heightwise of the post.

11. A clicking machine comprising a frame, a bed, a post mounted for reciprocation relatively to the frame, a presser member mounted upon the post for movement laterally over the bed about the axis of the post, power means for reciprocating the presser member, a handle extending along one side of the presser member and fixedly secured thereto, and means for initiating operation of the power means comprising a movable handle carried by the presser member and extending along one side thereof in proximity to the first-mentioned handle.

12. A clicking machine comprising a frame, a bed, a post mounted for reciprocation relatively to the frame, a presser arm carried by the post and movable laterally over the bed, power means for reciprocating the post, means for controlling the power means comprising a handle rigidly secured to and extending along one side of the arm, and a movable handle extending substantially parallel and adjacent to the first-mentioned handle.

13. A clicking machine comprising a frame, a bed, a post mounted in the frame, a presser member carried by the post and arranged for movement laterally over the bed, power means for reciprocating the presser member, means for controlling the power means comprising a movable handle mounted upon the presser member, and a fixed handle mounted upon the presser member adjacent to the movable handle in position to cooperate therewith in effecting manual operation of the movable handle.
